CLAIM

The ornamental design for an ingot mold, as shown and described.

DESCRIPTION

FIG. 1 is a bottom, front, and right side perspective view of an ingot mold;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

(Continued)

The broken lines are for illustrative purpose only and form no part of the claimed designs.

1 Claim, 7 Drawing Sheets
